(57) **CLAIM**

The ornamental design for a wearable device for measuring biological signal, as shown and described.

DESCRIPTION

1.1 is a front view of a wearable device for measuring biological signal showing our new design;

1.2 is a back view thereof;

1.3 is a top view thereof;

1.4 is a bottom view thereof;

1.5 is a right side view thereof;

1.6 is a left view thereof;

1.7 is a cross-sectional view thereof taken along line **1.7-1.7** in **1.6**;

1.8 is a cross-sectional view thereof taken along line **1.8-1.8** in **1.6**;

1.9 is an enlarged view of the central portion of the wearable device for measuring biological signal in **1.1**;

1.10 is a cross-sectional view thereof taken along line **1.10-1.10** in **1.9**;

1.11 is a perspective view thereof; and

1.12 is a reference perspective view thereof in a state in which a front panel and a back panel are joined.

This article is a wearable device for measuring biological signal on which an electrode sheet provided with electrodes for measuring biological signals such as an electrocardiogram and a biological signal measuring instrument such as an electrocardiograph can be detachably attached; and the dashed lines in the drawings depict portions of the wearable
